United States Patent Office

Des. 233,482

Patented Oct. 29, 1974

233,482

MICROFILM VIEWER

William A. Andres, Hopkins, Larry D. Quanrud, Minneapolis, Charles J. Koppa, Wayzata, Larry F. Becker and William K. Cristoffersen, Minneapolis, and James L. Keely, Wayzata, Minn., assignors to Washington Scientific Industries, Inc., Long Lake, Minn.

Filed Apr. 10, 1973, Ser. No. 349,776

Term of patent 14 years

Int. Cl. D16—03

U.S. Cl. D61—1 N

FIG 1

Fig. 1

Fig. 2

FIG.
1

FIG.
2

FIG. 1 is a right front perspective view of a microfilm viewer showing our new design;

FIG. 2 is a front elevational view thereof;

FIG. 3 is a right side elevational view thereof, the left side being a mirror image thereto;

FIG. 4 is a rear elevational view thereof;

FIG. 5 is a top plan view thereof.

We claim:

The ornamental design for a microfilm viewer, as shown.
